UNITED STATES PATENT OFFICE.

WALTER REMPT, OF SUHL, GERMANY.

SPORTING SHOTGUN.

Application filed December 24, 1925, Serial No. 77,559, and in Germany December 31, 1924.

According to this invention a shot-gun of the magazine type is so constructed as regards its coacting parts that the source of danger in handling it is reduced, the manipulation 5 itself is simplified and the coacting parts are made so simple that the whole gun in the combination of its parts forms a new model for shot-guns, in which the entire manufacture is made considerably cheaper.

10 According to one constructional form of the invention the chamber cover of the shot-gun is carried right to the side wall, preferably so as completely to close the chamber, only a small space being left between the 15 side wall and the cover as a guide which at the same time acts as a guide for a chamber boss. A portion of this narrow space or slot, the rear portion, may be covered by a plate which acts as a closing plate and the 20 front end of which acts as a stop for the bolt handle when the chamber is open, the handle being for instance provided with a notch or the like with which it engages over the plate. For further securing the locking a second 25 locking boss is provided on the bolt, which, on the lock moving backwards, releases securing means for the cartridge magazine, the said release taking place when the head of the lock is pulled back so far into the chamber 30 that the cartridge lying in the magazine, which is forced up by the cartridge elevator, can enter the chamber unobstructed. The securing means may consist for instance of a one-armed or two-armed lever, one arm of 35 which or a projection on the said arm engages in the cartridge magazine in such a manner that, when the parts are in the secured position, the top cartridge is forced out of the cartridge magazine against the 40 under surface of the projection or lever arm. On the bolt going back the second locking boss presses against a pin or stop member on the locking lever and causes the latter to move aside in such a manner that the outlet 45 opening of the magazine is no longer obstructed, so that the elevator can push the top cartridge into the chamber, after the spent cartridge has been thrown out by the ejector.

50 According to a further constructional form of the invention the nut of the breech-bolt is so connected to the striker and so guided in the bolt that, on the breech-bolt being pushed forward, it is held by the upwardly pressed spring loaded trigger and the breech-bolt head is

alone pushed into the locking position, while the nut of the breech-bolt with the striker is held until the trigger is pulled, whereupon the nut of the breech-bolt and the striker 60 shoot forward and are brought to rest in a known manner by the striker spring. By the holding back of the breech-bolt nut with the striker the gun is at the same time cocked. 65

As a means for further securing and positively guiding the head of the breech-bolt the cartridge extractor of the latter is so arranged as to be guided in a groove in the forward part of the breech casing and enters 70 this groove, when the breech-bolt is turned by means of the handle and the head of the breech-bolt also seeks to turn with it. Such an undesired lateral turning motion of the head of the breech-bolt is prevented by the 75 new construction of the extractor.

For considerably simplifying the manufacture of the cartridge magazine and the operation of the parts mounted therein, the former which is arranged to hold two or 80 more cartridges may be made of drawn material and be fixed to the trigger guard by any suitable means. The end walls of the magazine are provided with slots in which lugs on the cartridge follower are guided, 85 the forward slot being preferably taken higher than the rear one or right up to the top, in order that the nose of the cartridge is forced into the correct position for the sliding of the cartridge into the chamber or 90 the cartridge holder. The elevating spring for the cartridge follower is made of flat material and may be put together of separate parts with sharp or round bends, which is a very cheap method of manufacture as 95 compared with the spring bent from one piece, as the pieces are easier to cut and require little bending, which is a lengthy operation with good steel material.

In the accompanying drawing a constructional example of the invention is shown in nine figures.

Fig. 1 shows a perspective general view of the new sporting shot-gun with the chamber closed.

Fig. 2 is a side view of the breech-bolt with the breech-bolt casing and the magazine with the breech-bolt handle closed.

Fig. 3 is a plan view of Fig. 2, while

Fig. 4 shows a view from below of Fig. 2. In

Fig. 5 the lower parts of the breech mech-

anism are shown in longitudinal section and in

Fig. 6 in section on VI—VI of Fig. 5, while Figs. 7 and 8 show details and

Fig. 9 is a cross-section on IX—IX of Fig. 5.

As will be seen from Figs. 1 to 3 the top 1 of the chamber is extended almost to the side wall 2 of the latter so that only a small 10 slot 3 remains between the two, while at the forward end of the chamber such a large opening is left that the cartridge can be introduced and ejected. Otherwise the cartridge container or chamber is almost entirely closed, so that the cartridges cannot 15 jump out upwardly. The rear end of the slot 3 is closed by a screwed on or inserted cover plate 4, both the right-hand breech-bolt boss 10 and the root of the bolt handle 17 enter the slot 3 when pulling back the bolt, so that the said slot acts as a guide for 20 the right-hand bolt boss parts. The bolt handle 17 is also provided with a notch 18, which, when the chamber is open, slides 25 over the forward edge of the cover plate, so that the bolt handle is directly secured in this position. The trigger 19 of the trigger lever 20, which extends through the bottom 30 of the chamber in the usual manner and extends slightly above the upper edge of the same, engages, when the breech-bolt 6 is pushed forward by means of the bolt handle 17, in front of the forward edge of the nut 11 of the bolt, to which the striker 12 is 35 fixed, which is acted on in the usual manner by the striker spring 13 as is shown in Fig. 5. As soon as the trigger 19, 20 is operated and the projecting end of 19 has receded behind the upper edge of the bottom of the 40 chamber, the nut 11 of the breech-bolt with the striker 12 will shoot forward in the usual manner in the direction of the arrow 14 and effect the ignition. At the forward end of the breech-bolt 6 is a second boss 7 which 45 in the position of rest or when the chamber is open lies on the left-hand side of the chamber or the breech-bolt and is guided in a groove 5 open at both ends, which for 50 enabling the breech-bolt and the boss 7 of the same to be turned at the end of the forward motion is bent upwards, as is indicated at 5' in Fig. 5. The bosses 7' on the left-hand side of the head of the bolt enter the extension 9 of the groove 5 and terminate at 55 5" in the breech end of the barrel. The breech-bolt head 15" is provided on its right-hand side with the cartridge extractor 15 which, as shown in Fig. 6 is guided in a groove 16, when the breech-bolt head 15' arrives in the locking position. Below the 60 chamber and pivoted on the screw 21 is a two-armed lever 22, 23', the end 23 of which always seeks under the pressure of a spring 22' to enter the path of the cartridge magazine 65 (Fig. 6 and Fig. 4, position shown in

broken lines). On the end 22 of the lever is a stop member 25, the upper end of which projects into the path of the guiding groove 5 (Figs. 6, 7, 9) and strikes against the left-hand boss 7 on the breech-bolt, as soon as the latter is completely drawn back, as is shown for instance in Fig. 4. Through the boss 7 striking against the stop member 25 on the lever 22, the lever 22, 23' will be caused to swing in the direction of the arrow (Fig. 6) and to be brought into the position shown in full lines in Fig. 4, so that the space above the cartridge magazine is entirely unobstructed and the upper cartridge can be forced upwards out of the magazine under the action of the spring 28 by the follower 26. The follower 26 is guided by lugs 29 in slots 30, 30' of the casing 27 of the magazine, which is made of one piece or is drawn and is fixed to the trigger guard 31 by means of lugs 27'. The trigger guard is fixed to the chamber by screws 32 (only the forward one of which is shown).

What I claim is:

1. A sporting shot-gun of the magazine type, comprising in combination an almost closed chamber, a breech-bolt capable of sliding and turning in the said chamber, a handle on the breech-bolt, a boss on the breech-bolt in alignment with the root of the said handle, a second boss on the other side of the breech-bolt, a covered guide for the said second boss, a striker, a nut on the rear end of the breech-bolt capable of arresting the striker, a trigger mechanism capable of arresting the said nut, a trigger guard, a cartridge magazine fixed to the said trigger guard, a locking lever for the magazine capable of being released by the breech-bolt, a follower in the magazine for elevating the cartridges contained therein, vertical slots in the magazine walls for guiding the follower, an extractor on the head of the breech-bolt and means for securing the extractor against being turned before the breech-bolt is turned, as set forth.

2. A sporting shot-gun of the magazine type, comprising in combination a chamber, a breech-bolt capable of sliding and turning in the said chamber, a handle on the breech-bolt, a boss on the breech-bolt in alignment with the root of the said handle, a second boss on the other side of the breech-bolt, a covered guide for the said second boss, a cover for the said chamber extending almost to the side wall of one side of the chamber, the narrow slot thus formed constituting a guide for the first boss and handle on the breech-bolt, a striker, a nut on the rear end of the breech-bolt capable of arresting the striker, a trigger mechanism capable of arresting the said nut, a trigger guard, a cartridge magazine fixed to the said trigger guard, a locking lever for the magazine capable of being released by the breech-

- bolt, a follower in the magazine for elevating the cartridges contained therein, vertical slots in the magazine walls for guiding the follower, an extractor on the head 5 of the breech-bolt and means for securing the extractor against being turned before the breech-bolt is turned, as set forth.
3. A sporting shot-gun of the magazine type, comprising in combination a chamber, 10 a breech-bolt capable of sliding and turning in the said chamber, a handle on the breech-bolt, a boss on the breech-bolt in alignment with the root of the said handle, a second boss on the other side of the breech-bolt, a covered guide for 70 the said second boss, a striker, a nut on the rear end of the breech-bolt capable of arresting the striker, a trigger mechanism capable of arresting the said nut, a trigger guard, a cartridge magazine fixed 75 to the said trigger guard, an opening in the magazine for the passage of the cartridges, a locking lever for the magazine, a spring for keeping the said lever in front of the said opening, a stop member on the 80 locking lever capable of being engaged by the said second boss on the breech-bolt shortly before the end of its rearward motion for removing the lever away from the opening in the magazine until the entry of the next cartridge, a follower in the magazine for elevating the cartridges contained therein, vertical slots in the magazine walls for guiding the follower, an extractor on the head of the breech-bolt and means for 85 securing the extractor against being turned before the breech-bolt is turned, as set forth.
4. A sporting shot-gun of the magazine type, comprising in combination an almost closed chamber, a breech-bolt capable of 90 sliding and turning in the said chamber, a handle on the breech bolt, a boss on the breech-bolt in alignment with the root of the said handle, a second boss on the other side of the breech-bolt, a covered guide for 95 the said second boss, a nut on the rear end of the breech-bolt, a striker fixed to the said nut and guided in the bolt, a trigger mechanism capable of arresting the said nut and striker and cocking the gun during the 100 closing motion of the breech-bolt, a trigger guard, a cartridge magazine fixed to the said trigger guard, a locking lever for the magazine capable of being released by the breech-bolt, a follower in the magazine for elevating the cartridges contained therein, vertical slots in the magazine walls for guiding the follower, an extractor on the head of the breech-bolt and means for securing the extractor against being turned before the 105 breech-bolt is turned, as set forth.
5. A sporting shot-gun of the magazine type, comprising in combination an almost closed chamber, a breech-bolt capable of 110 sliding and turning in the said chamber, a handle on the breech-bolt, a boss on the breech-bolt in alignment with the root of the said handle, a second boss on the other side of the breech-bolt, a covered guide for 115 the said second boss, a striker, a nut on the rear end of the breech-bolt capable of arresting the striker, a trigger mechanism capable of arresting the said nut, a trigger guard, a cartridge magazine fixed to the said trigger guard, a locking lever for the magazine ca- 120
6. A sporting shot-gun of the magazine type, comprising in combination an almost closed chamber, a breech-bolt capable of 125 sliding and turning in the said chamber, a handle on the breech-bolt, a boss on the breech-bolt in alignment with the root of the said handle, a second boss on the other side of the breech-bolt, a covered guide for the said second boss, a striker, a nut on the rear end of the breech-bolt capable of arresting the striker, a trigger mechanism capable of arresting the said nut, a trigger guard, a cartridge magazine fixed to the said trigger guard, a locking lever for the magazine ca-

pable of being released by the breech-bolt, a follower in the magazine for elevating the cartridges contained therein, vertical slots in the magazine walls for guiding the follower, an extractor on the head of the breech-bolt, a lateral groove in the chamber in which the extractor is capable of engaging for securing the extractor against being turned before the breech-bolt is turned by 10 the handle, as set forth.

8. A sporting shot-gun of the magazine type, comprising in combination an almost closed chamber, a breech-bolt capable of sliding and turning in the said chamber, a handle on the breech-bolt, a boss on the breech-bolt in alignment with the root of the said handle, a second boss on the other side of the breech-bolt, a covered guide for the said second boss, a striker, a nut on the 15 rear end of the breech-bolt capable of arresting the said nut, a trigger guard, a cartridge magazine of drawn material capable of holding a plurality of cartridges and fixed to the said trigger guard, a locking lever for the magazine capable of being released by the breech-bolt, a follower in the magazine for elevating the cartridges contained therein, vertical slots in the magazine walls for guiding the follower, an extractor on the 20 head of the breech-bolt and means for securing the extractor against being turned before the breech-bolt is turned, as set forth.

9. A sporting shot-gun of the magazine type, comprising in combination an almost closed chamber, a breech-bolt capable of sliding and turning in the said chamber, a handle on the breech-bolt, a boss on the breech-bolt in alignment with the root of the said handle, a second boss on the other 35 side of the breech-bolt, a covered guide for the said second boss, a striker, a nut on the rear end of the breech-bolt capable of arresting the striker, a trigger mechanism capable of arresting the said nut, a trigger guard, a cartridge magazine fixed to the said trigger guard, a locking lever for the magazine capable of being released by the breech-bolt, a follower in the magazine for elevating the cartridges contained therein, lugs on the 40 said follower, vertical slots in the front and rear walls of the magazine for guiding the said lugs, an extractor on the head of the bolt and means for securing the extractor against being turned before the breech-bolt is turned, as set forth.

10. A sporting shot-gun of the magazine type, comprising in combination an almost closed chamber, a breech-bolt capable of sliding and turning in the said chamber, a handle on the breech-bolt, a boss on the breech-bolt in alignment with the root of the said handle, a second boss on the other side of the breech-bolt, a covered guide for the 60 said second boss, a striker, a nut on the rear end of the breech-bolt capable of arresting

the striker, a trigger mechanism capable of arresting the said nut, a trigger guard, a cartridge magazine fixed to the said trigger guard, a locking lever for the magazine capable of being released by the breech-bolt, a follower in the magazine for elevating the cartridges contained therein, lugs on the said follower, vertical slots in the front and rear walls of the magazine for guiding the said lugs, the front slot extending higher than the rear slot, an extractor on the head of the bolt and means for securing the extractor against being turned before the breech-bolt is turned, as set forth.

11. A sporting shot-gun of the magazine type, comprising in combination an almost closed chamber, a breech-bolt capable of sliding and turning in the said chamber, a handle on the breech-bolt, a boss on the breech-bolt in alignment with the root of the said handle, a second boss on the other side of the breech-bolt, a covered guide for the said second boss, a striker, a nut on the rear end of the breech-bolt capable of arresting the striker, a trigger mechanism capable of arresting the said nut, a trigger guard, a cartridge magazine fixed to the said trigger guard, a locking lever for the magazine capable of being released by the breech-bolt, a follower in the magazine for elevating the cartridges contained therein, lugs on the said follower, vertical slots in the front and rear walls of the magazine for guiding the said lugs, the front slot extending to the top of the front magazine wall, an extractor on the head of the bolt and means for securing the extractor against being turned before the breech-bolt is turned, as set forth.

12. A sporting shot-gun of the magazine type, comprising in combination an almost closed chamber, a breech-bolt capable of sliding and turning in the said chamber, a handle on the breech-bolt, a boss on the breech-bolt in alignment with the root of the said handle, a second boss on the other side of the breech-bolt, a covered guide for the said second boss, a striker, a nut on the rear end of the breech-bolt capable of arresting the striker, a trigger mechanism capable of arresting the said nut, a trigger guard, a cartridge magazine fixed to the said trigger guard, a locking lever for the magazine capable of being released by the breech-bolt, a follower for the cartridges in the magazine, a composite flat spring, the bends of which are partly sharp and partly round, for elevating the said follower, vertical slots in the magazine walls for guiding the follower, an extractor on the head of the breech-bolt and means for securing the extractor against being turned before the breech-bolt is turned, as set forth.

In testimony whereof I have signed my name to this specification.

WALTER REMPT.
